HAIRDRESSING TOOL

Herman C. Schlicker, Brooklyn, N. Y., assignor to
 Rollocurl Corporation, New York, N. Y., a corporation of New York

Application October 26, 1938, Serial No. 237,118

11 Claims. (Cl. 132—35)

The present invention relates to hair-dressing tools, and is more particularly directed toward disappearing combs with or without devices for supporting a hairpin to facilitate making of curls.

The present invention contemplates an inexpensive form of hair-dressing tool having both the regular comb adapted for heavy duty when combing the head of hair, and a small disappearing comb carried in the element which forms the handle for the first-mentioned comb as well as a mandrel, so that one can use the same tool for either combing the hair, or forming the coil.

A further object of the invention is to provide a hair-dressing tool having a disappearing comb adapted to be manually shifted from the projected to the retracted positions and locked in with position and having a spring bearing on the back of the insert to hold the insert in the outer or projected position, the disappearing comb insert being completely removable for cleaning.

A further object of the invention is to provide a hair-dressing tool having a disappearing comb and wherein the body member, which forms a mandrel for winding the coil of hair, has a short extension with associated means for holding a hairpin in such a position while the coil of hair is being wound that it can be pushed toward the coil and spread so as to receive the coil when slid off the end of the mandrel.

A further object of the present invention is to provide an insert for disappearing combs having a reinforcement which prevents the insert from bending out of shape owing to the pressure of the spring below it.

Other and further objects will appear as the description proceeds.

The accompanying drawing shows, for purposes of illustrating the present invention, two of the many embodiments in which the invention may take form, it being understood that the drawing is illustrative of the invention rather than limiting the same.

In the drawing:

Figure 1 is a longitudinal sectional view with parts in elevation showing a hair-dressing tool having both forms of comb, the disappearing comb being shown in two positions;

Figure 2 is a view similar to Figure 1 illustrating a form of construction having in addition the means for supporting a hairpin, the hairpin being in position to allow winding the coil of hair;

Figure 3 is a top elevational view of the structure shown in Figure 2;

Figure 4 is a view illustrating the coil of hair wound on the hair-dressing tool, the hairpin

pushed in and spread and a modified form of release for securing the disappearing comb against removal;

Figure 5 is a transverse sectional view on the line 5—5 of Figure 2 at an enlarged scale;

Figure 6 is a transverse sectional view at an enlarged scale taken on the line 6—6 of Figure 2;

Figure 7 is a cross section on the line 7—7 of Figure 1; and

Figure 8 is a sectional view of the securing device of Figure 4.

The hair-dressing tool shown in Figure 1 has a body member 10 formed of suitable material. The end 10a has a series of heavy strong teeth 11 to form a comb for combing the hair, while the other end 10b of the body member is of generally rectangular cross section and has a longitudinally extending slot 12 which terminates near the end of the body member. The extreme end 20 of the slot 12 has two longitudinally extending openings 13 and 14. The body member carries a transversely extending pin 15.

A movable insert 16 is received in the slot 12. This insert has a backing part 17, and a series of comb teeth 18. It has a pin-like extension 19 at the end of the backing and a thumb piece 20 opposite a laterally extending slot 21 which opens rearwardly so that the insert can be easily inserted or removed. The slot has short branches 22 and 23 and the parts are so spaced that the insert can be shifted longitudinally and laterally so that the selected slot in the insert passes along the pin 15. The comb insert is urged outwardly by a spring indicated at 24 and is normally kept in place by engagement of the pin 19 with the element 25 on the body member and by the engagement of the right-hand end 26 with an overlying spring 27. This spring carries a button 28 in a notch 29 so that the spring can be bent back as indicated in dotted lines (Figure 3) to release the insert.

Owing to the smallness of the parts and the application of spring pressure to the backing 17 of the insert, it is desirable to reinforce this backing by providing some form of metal stiffener as shown at 29' in Figure 7. The stiffener may be secured during the molding operation or mechanically. When the insert is in the position shown in Figure 1, the comb teeth are below the surface 50 of the mandrel forming element 10b and the insert is held in this position by the pin-like extension 19 in the lower opening 13 and by the pin-like extension 15 entering the branch 23 of the slot. Shifting the insert to the right will disconnect these interlocking connections and the

spring will force the insert out to the dot-and-dash line position of Figure 1 which is the full line position of Figure 2. The insert can then be slid to the left, as shown in Figure 2, and the parts again interlocked so that the insert will not be pressed down while the tress of hair is being combed out.

In the arrangement shown in Figures 2 to 5, inclusive, the parts above described are also employed. The body member, however, has a short extension 30 to which is secured a sheath 31, for example, by a hollow rivet such as shown at 32. The lower part of this sheath is spaced below the lower part of the extension 30 as indicated at 33. The extension also supports a spring 34 which is adapted to be bent when the shank 35 of a hairpin 36 is inserted. When the parts are in the position shown in Figures 2 and 3, the tress of hair can be combed out and the coil started. The disappearing comb is then pushed back into the body member and locked in position and after the tress has been completely wound on the mandrel the hairpin can be pushed from the position shown in Figures 2 and 3 from the position shown in Figure 4 where it is spread and in a position to receive the coil of hair as it is pushed off the mandrel.

An alternative form of securing device for the end of the insert is shown at 37, Figures 4 and 8.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. A hair-dressing tool comprising a body member having a longitudinally extending slot, a toothed insert received in the slot for lateral and longitudinal movement and having a thumb piece projecting laterally from the slot for pressing the insert into the slot and shifting it longitudinally, one end of the insert having a longitudinally extending pin-like projection the other end having a laterally extending inwardly opening slot with two longitudinally extending branches, the body member having a transversely extending element received in the slot and two openings for receiving the pin-like extension whereby the insert may be held in either retracted or projected position, and a spring for shifting the insert to the projected position.

2. A hair-dressing tool such as claimed in claim 1, wherein the said other end has an extension and the body member has a releasable stop to engage the same.

3. A hair-dressing tool comprising a body member having a longitudinally extending laterally opening slot, the slot having longitudinal extensions spaced different distances from the open edge of the slot, and a comb-toothed insert longitudinally and laterally movable in the slot, the insert having a pin-like extension at one end to fit the one or the other of the slot extensions, the other end of the insert and the body member having a pin and slot connection permitting lateral movement when the pin-like extension is out of the slot extension and for permitting longitudinal movement when the pin-like extension is aligned with either of the slot extensions.

4. A hair-dressing tool comprising a body member having a longitudinally extending laterally opening slot, a transversely extending pin, 75

an insert having comb teeth and a body part, the body part having a rearwardly opening laterally extending slot to receive the pin and longitudinally extending branches of the slot 5 into which the pin enters when the insert is moved longitudinally of the slot in the body member, and a spring carried in the body member slot and urging the insert laterally out of the said slot.

10 5. An insert for disappearing combs comprising a backing having a series of laterally extending comb teeth, a pin-like extension at one end, a thumb piece at the other end, the material forming the thumb piece having a rearwardly opening L-shaped slot.

15 6. A curling device comprising a member having a handle and an elongated body of substantially oblong rectangular cross section with a slot opening through one edge margin, a comb member slidably arranged in said slot, spring means acting against said comb member to urge it outwardly to projected position, said comb being endwise shiftable in said slot, and means rendered effective by endwise movement of said comb member when housed in one longitudinal direction for locking it in housed position.

20 7. A curling device comprising a member having a handle and an elongated body of substantially oblong rectangular cross section with a slot opening through one edge margin, a comb member slidably arranged in said slot, spring means 30 acting against said comb member to urge it outwardly to projected position, said comb member being capable of endwise movement in said slot, and said body and said comb member having means engageable on longitudinal movement of said comb member in the same direction in either of two positions for locking the comb member in its then position.

25 8. In a device of the class described, means providing a slotted housing, a comb member slideable within said housing between projected operative position and housed inoperative position, said comb member having a thumb seat formed at one end and having a C-shaped slot formed in said thumb end of said comb member with legs of said slot vertically spaced and extending in the direction of the length of the member, a pin engaged in said housing and working in said comb member slot adapted to be engaged by either of said slot legs to hold said comb in selected position with respect to said slot.

35 9. In a device of the class described, means providing a slotted housing, a comb member slideable within said housing between projected operative position and housed inoperative position, said comb member having a thumb seat formed at one end and having a C-shaped slot formed in said thumb end of said comb member with legs of said slot vertically spaced and extending in the direction of the length of the member, a pin engaged in said housing and working in said comb member slot adapted to be engaged by either of said slot legs to hold said comb in selected position with respect to said slot, the other end of said comb member being provided with a projection for engaging notches in the end of said housing when said comb member is shifted to hold said other end of said comb member in substantial alignment with the rear end of said member as determined by engagement of said slot legs with said pin.

40 10. In a device of the class described, means providing a slotted housing, a comb member slideable within said housing between projected operative

ative position and housed in operative position, said comb member having a thumb seat formed at one end and having a C-shaped slot formed in said thumb end of said comb member with legs of said slot vertically spaced and extending in the direction of the length of the member, said comb member and body having cooperating pin and notch means which become engaged when the comb member is moved longitudinally in said one direction to hold the other end of said comb member in locked position corresponding to the locked position of said one end.

11. A hair-dressing tool comprising a body member having a longitudinally extending slot, a

toothed insert received in the slot for lateral and longitudinal movement and having a thumb piece projecting laterally from the slot for pressing the insert into the slot and shifting it longitudinally, the ends of the insert and the opposed portions of the body member having interlocking elements acting on longitudinal movement of the insert in one direction to hold it in either the retracted or the projected position, a spring for shifting the insert to the projected position when the insert is moved longitudinally to separate the interlocking elements, and a stiffener on said insert for resisting bending of said insert by said spring.
